UNITED STATES PATENT OFFICE

ALLAN L. McGREGOR, OF CHICAGO, ILLINOIS.

AUTOMOBILE-BUFFER.

1,032,690.

Specification of Letters Patent. Patented July 16, 1912.

Application filed November 13, 1911. Serial No. 659,331.

To all whom it may concern:

Be it known that I, ALLAN L. McGREGOR, a citizen of the United States, residing at Chicago, in the county of Cook and State of Illinois, have invented certain new and useful Improvements in Automobile-Buffers, of which the following is a specification.

This invention relates to buffers or bumpers used on automobiles, and has reference 10 more particularly to that type of buffer now quite extensively used, wherein a horizontally disposed buffer-bar is yieldably mounted upon and in advance of the forwardly projecting ends of the machine frame.

15 The leading object of the invention is to provide a simple, inexpensive, and highly efficient device for the purpose stated, capable of ready application to the machine frame without the necessity of drilling or cutting the latter to accommodate the attaching means, and wherein the buffer bar itself is rendered vertically adjustable within certain limits by adjusting means which 20 coöperate with the other parts in maintaining the buffer-bar rigidly in adjusted position against vertical displacement while at the same time permitting full freedom of inward and outward movement to the extent afforded by the cushioning devices.

25 My invention, its structural features, mode of use, and practical advantages, will all be apparent from a consideration of the following description, taken in connection with the accompanying drawing which illustrates one practical form in which the invention may be dressed, and in which—

30 Figure 1 is a top plan view of my improved automobile buffer, showing the same as mounted on the forward end of the vehicle frame. Fig. 2 is an enlarged side elevation, in cross-section through the buffer bar. Fig. 3 is a further enlarged cross-section on the line 3—3 of Fig. 2.

35 Referring to the drawing, 10 designates the forwardly and downwardly curved end portions of the usual side bars of the machine frame, to the forward ends of which are pivoted by hinge bolts 11 the usual semi-elliptic springs 12.

40 13 designates the buffer bar. The particular form of this bar is immaterial to the present invention, but in its preferred form it is made with an inwardly disposed flat horizontal web; the bar herein shown being 45 of T-bar form with its central web 13' disposed inwardly or toward the front end of

the vehicle. The web 13' is provided with two series of bolt holes 14 to facilitate the attachment thereto of a pair of buffer-bar carrying arms 15, which, as herein shown, 50 have forked forward ends or heads 15' that straddle the web 13' and are apertured to receive fastening bolts 16 that pass through one of the holes 14 of the buffer-bar near the opposite ends of the latter. 55

The carrying arms 15 are guided and supported in a pair of barrels 17, each of which is formed with a rigid integral rearwardly extending arm 18, and, on its under side and adjacent to its front end with a 60 pair of apertured depending lugs or ears 19 (Fig. 3). The arms 18 are secured at their inner or rear ends to the upper and rear ends of a pair of clamps rigidly secured to the side bars 10. Each of these clamps, as herein 65 shown, comprises a forwardly and downwardly curved upper clamp-plate 20 having a pair of apertured lateral lugs 21, a pair of narrow clamp-plates 22 disposed transversely of the underside of the side bar 10 70 and having apertured ends, and clamp-bolts 23 connecting the lugs 21 with the ends of the clamp-plates 22 on each side of the side bar 10. The upper clamp-plate 20 is further provided on its upper surface and at 75 its rear end with a pair of upstanding lugs or ears 24 between which the inner end of the arm 18 is secured by a bolt 25. The lower end of the upper clamp-plate 20 extends down slightly below the knuckle or 80 pivot-joint formed between the side bar 10 and spring 12, and such lower end portion is bifurcated or forked and apertured to form a pair of pivot-lugs or ears 26, as clearly 85 shown in Fig. 3. Secured at its upper end between the lugs 19 of the barrel 17 by a bolt 27 is another supporting arm or brace 28 for the barrel 17, the lower portion of which engages the lower end of the clamp-plate 20 between the pivot-lugs or ears 26 90 thereof and is provided with a series of holes 29 by which the arm 28 may be secured through the agency of a bolt 30 in any one of a number of adjusted positions, so as to vary, within the limits afforded by the number of holes 29, and their distance apart, the height of the buffer bar 13 relatively to the vehicle frame. The arm or brace 28 not only serves as an adjusting means affecting 95 the height of the buffer-bar, but it also co-operates with the rigid arm 18 in securing a very strong and rigid support of the

105

110

115

guide-barrel 17 and the parts carried thereby on the clamp.

Surrounding the carrying arms 15 and confined endwise between the heads 15' and 5 the forward ends of the guide-barrels 17 are a pair of coiled cushioning springs 31; and the inner ends of the carrying arms 15 normally project slightly beyond the inner ends of the guide-barrels 17 and are provided with cotter-pins 32 that coöperate with the inner ends of the barrels 17 to 10 limit the forward movement of the arms 15 and buffer-bar under the thrust of the springs.

15 From the foregoing it will be seen that my improved buffer is of simple and economical construction, is capable of a considerable range of vertical adjustment of the buffer-bar, affords a strong and rigid support for the guides of the buffer-bar carrying arms, and distributes the strain of an inward thrust of the buffer-bar over a considerable portion of the side sill 10. One of 20 the commonest conditions under which these buffer-bars are called into action occurs where a vehicle backs down upon the front end of an automobile, the rear wheels of the vehicle striking the buffer-bar and imparting thereto not only an inward thrust 25 but a strong downward thrust. The device of my present invention is especially well adapted to resist the effect of such collisions since the arms 28, in such cases, constitute a very effective form of brace to resist such 30 downward swing of the buffer-bar and confine its yielding movement to a straight inward movement.

It will be evident to those skilled in the art that the particular forms and relative 35 arrangement of parts described might be varied in detail without involving any departure from the principle of the invention or sacrificing any of the advantages thereof. Hence, I do not limit the invention to the 40 exact structure disclosed, except to the extent clearly indicated in specific claims.

I claim—

1. An automobile buffer, comprising, in combination, a buffer-bar, clamps adapted to be secured to the side bars of the vehicle 50 frame, buffer-bar carrying arms, guides in which said arms are slidably mounted, cushioning springs for said buffer-bar, means for pivotally connecting one end of each guide to one of said clamps, and means for adjustably connecting the opposite end of the said guide to said clamp whereby to rigidly support said guide in any of plurality of adjusted positions, substantially as described.

2. An automobile buffer, comprising, in combination, a buffer-bar, clamps adapted to be secured to the side bars of the vehicle frame, buffer-bar carrying arms, guides in which said arms are slidably mounted, 55 cushioning springs for said buffer-bar, means for pivotally connecting the rear end of each guide to the rear end of one of said clamps, and means for adjustably connecting the forward end of the said guide to the 60 forward end of said clamp, substantially as described.

3. An automobile buffer, comprising, in combination, a buffer-bar, clamps adapted to be secured to the side bars of a vehicle frame, 75 and at their forward ends overlying the forward ends of the latter, buffer-bar carrying arms, tubular guides in which said arms are slidably mounted, cushioning springs encircling said arms in advance of said guides, 80 rigid rearwardly extending arms on said guides pivotally connected to the rear ends of said clamps, and other downwardly extending arms connected at their upper ends to the forward portions of said guides and 85 at their lower ends adjustably connected to the forward ends of said clamps, substantially as described.

ALLAN L. McGREGOR.
